UNITED STATES PATENT OFFICE.

CHARLES L. EMMONS, OF CRANFORD, NEW JERSEY, ASSIGNOR TO THE AEOLIAN COMPANY, A CORPORATION OF CONNECTICUT.

ADJUSTABLE TRACKING DEVICE.

1,330,065.

Specification of Letters Patent. Patented Feb. 10, 1920.

Application filed April 21, 1917. Serial No. 163,639.

To all whom it may concern:

Be it known that I, CHARLES L. EMMONS, a citizen of the United States, and a resident of Cranford, county of Union, and

5 State of New Jersey, have invented certain new and useful Improvements in Adjustable Tracking Devices, of which the following is a specification, reference being had to the accompanying drawing, forming a part 10 thereof.

My invention relates to new and useful improvements in automatic tracking devices for mechanical players for musical instruments, and its object is to provide a simple 15 and effective adjusting device therefor.

I will describe in the following specification the present invention, and will point out the novel features thereof in appended 20 claims.

25 Referring to the drawings:

Figure 1 is a front elevation of a part of a player piano or the like with a mechanism which embodies my invention applied thereto.

25 Fig. 2 is a plan view of a part of the mechanism shown in Fig. 1.

Fig. 3 is a front elevation of the parts shown in Fig. 2.

Like characters of reference designate 30 corresponding parts in all the figures.

10 designates a perforated music sheet which, during the operation of the instrument, is unwound from the music roll spool 11 onto a motor-driven take-up spool 12,

35 over a perforated tracker bar 13 on the front of a casing 14. During this operation it is necessary to have the music sheet in such a position transversely in respect of the stationary tracker bar that the note perforations therein are in accurate registering alignment with their respective ducts in the tracker bar. To this end means are pro-

40 vided for automatically shifting the music roll spool 11 longitudinally, which I will 45 now describe.

20 is a frame to which the tracker bar casing is affixed and in which the bearings for the music roll spool and the take-up spool clutches are mounted. 21 is a longitudinally 50 movable rod for the music roll clutch 22. This is pressed to the right by means of a

24 is a similar movable rod for the music roll spool clutch 25 which is pressed to the left by a lever 26 which is pivotally supported at 27.

30 is a pneumatic which is connected with the suction bellows of the instrument by a tube 31 so that during the operation of the instrument this pneumatic has a tendency to 55 collapse. A rod 32 is connected from the movable side of the pneumatic to the lever so that when this pneumatic collapses, the rod 24 and the music roll spool 11 are moved to the left thereby against the action 60 of the spring 23.

33 is a flexible tube from the pneumatic to a tube 34, the end of which constitutes a port. This is supported in a movable member 40 in the tracker bar casing at one 70 end thereof. 41 is a valve on a lever 42, pivoted at 43 to the member 40 and spring-pressed against the port or mouth of the tube 34. The end of lever 42 forms a finger 44 which passes through an opening 45 in 75 the tracker bar at the edge of the music sheet.

From the foregoing description it may be seen that if the position of the music roll is too far to the right, its left hand edge 80 will not touch the finger 44. Under these conditions the valve 41 will be closed and the pneumatic 30 will collapse and will thereby shift the music roll spool 11 and the music roll 10 to the left.

If the music roll is too far to the left its edge will press against finger 44 and lift valve 41 from the valve seat. This will allow air to pass through tube 33 into the pneumatic 30, thus neutralizing the vacuum 90 therein which has caused the pneumatic to collapse so that the pneumatic will return to its expanded condition,—that shown in Fig. 1,—to remove the pressure of lever 26 from rod 24 and this allows spring 23 to 95 shift rod 21, the music roll spool 11 and the music sheet 10 to the right.

The parts are so proportioned and adjusted that the music roll spool 11 floats longitudinally between the end pressure of the 100 spring 23 and that produced by the collapsing tendency of the pneumatic with the music sheet maintained in tracking position.

This operation is a matter of delicate pro-

portioning and arrangements of parts. In fact, it is easily disturbed by the swelling or shrinkage of the paper of the music sheet. To make such an apparatus more reliable and useful, I propose to provide a convenient manual adjustment for the part of such an apparatus which coöperates with the music sheet. In the form of mechanism which I have chosen to illustrate my invention, the ported member 40 is mounted on a spring 50 which has a tendency to move the member 40 and its valve together with the finger 44 to the left. The extent of this movement to the left is limited by a nut 51 between the frame 20 and the adjacent side of the ported member. The nut is mounted on an adjusting screw 52 which has a knurled head 53, the upper edge of which projects through the casing 14 directly back of tracker bar 13. The edge 54 of member 40 which abuts against nut 51 is inclined so that when nut 51 is moved outward, valve box 40 and finger 44 are moved to the left, and when nut 51 is moved back, these parts are moved to the right.

Thus, by this device a ready and accurate adjustment of the tracking device may be obtained. It is obvious that this adjustment may be made while the instrument is in operation without interfering with any of its other functions. I do not intend to limit myself to any specific form or construction of parts and in fact intend only such limitations as are imposed in the appended claims.

What I claim is:

1. In an automatic tracking device, a tracker bar, longitudinally movable supports for a music roll spool, a spring arranged to move said supports in one direction, a pneumatic arranged to move said supports in the opposite direction, a movable ported member at one side of the tracker bar, a valve therefor near said tracker bar, a valve lever pivotally supported by said member, said lever comprising a finger adapted to be at the edge of the music sheet as it passes over the tracker bar to coöperate with the edge of the music sheet to control the pneumatic, a spring supporting said movable member and tending to move said member in one direction, and an adjusting screw manually operable during the movement of the music sheet over the tracker bar arranged to limit the spring-impressed movement of said member,

and to determine the position of said member and the finger in relation to the tracker bar.

2. In an automatic tracking device, a tracker bar casing, a tracker bar, longitudinally movable supports for a music roll spool, a spring arranged to move said supports in one direction, a pneumatic arranged to move said supports in the opposite direction, a movable ported member in the tracker bar casing, a valve therefor near said tracker bar, a valve lever pivotally supported by said member, said lever comprising a finger projecting through the tracker bar and adapted to be at the edge of the music sheet as it passes over the tracker bar to coöperate with the edge of the music sheet to control the pneumatic, a spring supporting said movable member and tending to move said member in one direction, and a manually operable adjusting screw having a knurled head projecting above the tracker bar casing near one end of the tracker bar, arranged to limit the spring-impressed movement of said member, and to determine the position of said member and the finger in relation to the tracker bar.

3. In an automatic tracking device, a tracker bar casing, a tracker bar, longitudinally movable supports for a music roll spool, a spring arranged to move said supports in one direction, a pneumatic arranged to move said supports in the opposite direction, a movable ported member in the tracker bar casing, a valve therefor near said tracker bar, a valve lever pivotally supported by said member, said lever comprising a finger projecting through the tracker bar and adapted to be at the edge of the music sheet as it passes over the tracker bar to coöperate with the edge of the music sheet to control the pneumatic, a spring supporting said movable member and tending to move said member in one direction, and a manually operable adjusting screw having a knurled head projecting above the tracker bar casing near one end of the tracker bar, a nut movable on said adjusting screw, the adjacent side of the ported movable member being inclined and arranged to be pressed against said nut by the supporting spring, whereby the spring-impressed movement of the ported member and the valve finger is determined.

In witness whereof, I have hereunto set my hand this 19 day of April, 1917.

CHARLES L. EMMONS.
